卷之三

UNITED STATES PATENT OFFICE

GORDON I. WATTERS, OF KNOXVILLE, ILLINOIS, ASSIGNOR TO JAMES V. KENNEDY, OF JACKSONVILLE, ILLINOIS

VENDING MACHINE

Application filed June 12, 1929. Serial No. 370,315.

The present invention relates to vending machines for candy or other suitable and desirable commodity, and has for an object to provide certain detail improvements in machines of this character, which will make for more economical manufacture and more reliable and economical up-keep and use of the machine.

The invention aims to provide a novel simplified construction of check controlled ejecting device combined with a coin releasing mechanism, wherein the number of movable parts are reduced to a minimum, and wherein the parts are so constructed, arranged and braced with relation to one another and to the other parts of the machine that a strong effective and simple constructed device is produced.

A further object of the invention is to provide an article ejecting device, which when actuated ejects the articles one at a time from the bottom of a stack located in the magazine, and to provide an ejector with a tail piece or portion adapted to follow the ejected article and maintain the remainder of the stack in elevated position out of the way until the ejecting device is brought back to normal position, wherein the tail piece is adapted to release the stack, so that the same may be lowered into position for the ejection of the next succeeding article.

The above and various other objects and advantages of this invention will in part be described in, and in part be understood from the following detailed description of the present preferred embodiment, the same being illustrated in the accompanying drawings, wherein:

Figure 1 is a front elevation of a candy vending machine constructed according to the present invention.

Figure 2 is a vertical section taken through the same.

Figure 3 is an enlarged horizontal section taken through the lower portion of the magazine on the line 3-3 of Figure 2.

Figure 4 is an enlarged longitudinal vertical section taken from front to back

through the machine in normal position after receipt of a coin.

Figure 5 is a similar view showing the plunger approaching its innermost position.

Figure 6 is a detail longitudinal section taken through the check controlled plunger and adjacent parts in the initial return position.

Figure 7 is a similar view showing the check immediately prior to being released.

Figure 8 is a fragmentary longitudinal section through the plunger and adjacent parts in position of compression without the check.

Figure 9 is an enlarged rear elevation of one of the units of the machine.

Figure 10 is an enlarged detail sectional view of two adjacent check chutes and adjacent parts, showing the deflecting magnet for removing spurious coins from the plunger mechanism.

Figure 11 is a transverse section taken through the check holding socket and adjacent parts on the line 11-11 of Figure 4.

Referring now to the drawings 20 designates a cabinet or casing suitably designed and of such dimensions as to properly house the various instrumentalities and to adapt the machine to lightness in weight and for support either upon a counter or against a wall, post or the like.

Within the cabinet 20 is disposed a magazine 21 of any suitable construction and adapted to combine a plurality of stacks of commodities 22 which may be candy or the like and to which the magazine compartments are adapted so as to feed the articles downwardly for delivery to the delivery spout 23. Beneath each magazine compartment there is disposed an upright standard or frame part 24 to a rear side of which is pivoted an arm 25, the latter having its lower end mounted on a rod 26 or the like extending through the lower portion of the frame 24 so that the arm 25 may swing rearwardly and downwardly and when swung upwardly into substantially vertical position

to engage the rear side of the frame 24 and thus maintain an upright vertical position of 100

rest of the arm 25. The arm 25 extends above the frame 24 and into close proximity to the magazine 21. An ejector 27 is mounted on the upper end of the arm 25.

The ejector comprises a substantially flat plate extending forwardly and rearwardly from the upper end of the arm 25 and in suitable spaced relation beneath the magazine 21. The forward end of the ejector 27 is offset upwardly to provide a contact shoulder 28 adapted to engage against the forward edge of the lowermost article of the stack 22 and to carry the article on the ejector plate 27 rearwardly from the stack and to dispose it at an inclination such that the article will automatically slide from the plate 27 into the delivery spout 23. This ejector device is provided at the upper end of the shoulder 28 with a tail piece 29, which forms a continuation of the plate 27 as to width and which is of considerable length. The tail piece 29 is, however, curved forwardly and downwardly from the shoulder 28 on an arc whose radius is projected from the pivot pin 26 as a center so that as the plate 27 is swung backwardly and downwardly the apron 26 wipes across the under side of the stack 22 of articles and maintains the articles in raised or elevated position and from escape from the magazine until the ejector is returned to upright or normal position with the plate 27 beneath the stack 22 and the shoulder 28 moved beyond the forward edge of the stack.

The ejector 27 is maintained in normal position with its carrying arm 25 in vertical position by a coil spring 30 or the like, the latter preferably having one end attached to the upper portion of the arm 25 and its other end attached to a cross brace 31 carried on the frame 24. Mounted for sliding longitudinal movement in the cross brace 31 and the rear portion of the frame 24 is a plunger rod 32 the rear end of which is held by the frame 24 in line with the arm 25, so that when the plunger rod 32 is projected rearwardly the arm 25 is pushed by the rod 32 rearwardly and downwardly, the rod having a free sliding movement against the forward face of the arm 25. The plunger rod 32 is normally urged forwardly by the arm 25 under the influence of the spring 30. The rod 32 is maintained by a cross pin 33 from sliding out of the frame 24 and the brace 31. The frame 24 is provided in spaced relation forwardly of the brace 31 with a coin socket 34 of suitable construction for the reception of a coin and provided in its rear face with a seat or depression 35 of a size sufficient to receive a coin of the selected denomination. The lower portion of the coin slot 35 is contracted or reduced so as to engage and hold the coin from slipping downwardly from the holder 34.

The holder 34 opens into a coin slot 36 of

suitable construction and which is rigidly mounted in the cabinet 20 and is preferably rigidly connected with the coin holder 34. The coin slot 36 extends upwardly in the desired manner and opens through the outer wall of the cabinet 20 to receive the coins or checks. The coin holder 34 which comprises the lower end of the coin chute 36 is provided upon its forward side with a pair of over-turned and downwardly directed hooks 75 36' which are adapted to engage over the upper edge of the cross plate 37' which is fixed in the frame 24. The coin holder 34 with the chute 36 is thus permitted a slight adjustment with respect to the plate 37' without disturbing the relative close relationship therebetween. 80

The coin holder 34 is provided substantially concentrically within the depression 35 with an opening 37 which receives slidably the rear end of a hollow plunger 38. The plunger 38 is of tubular form suitably flanged at its rear end to engage and seat in the opening 37 so that the coin holder provides means for limiting the forward ejection of the plunger 38. The plunger 38 extends forwardly from the coin holder 34 through the front of the frame 24, and between the frame 24 and the coin holder or plate 34, an expanding coil spring 39 is mounted. The spring 39 surrounds the plunger 38, bears at one end against the coin holder 34 and at its other end engages a cross pin 40, which is secured through the intermediate portion of the plunger 38 and against which the spring is adapted to press for urging the plunger 38 normally forward. The plunger 38 projects outwardly from the cabinet 20 in any suitable manner and to any suitable distance, and may be provided with a knob, head or like portion 41 upon its outer end adapted to be engaged for forcing the hollow plunger 38 backwardly. 90

The plunger 38 is held in direct axial alignment with the plunger rod 32 and is adapted to receive the forward end of the latter when the plunger 38 is depressed without a coin or other check disposed in the recess or socket 35 of the coin holder. 100

Arranged beneath the forward end of the plunger rod 32 is a coin tripping dog 42 pivoted at 43 upon a bracket 44 mounted on the frame 24 so as to hold the nose of the dog 42 upwardly into the path of the coin when seated in the socket 35. The pawl 42 is so mounted as to incline upwardly and rearwardly, and as the plunger 38 and plunger rod 32, interconnected by a coin or check, such as 45, with the coin rides over the upper edge of the pawl 42 the pawl 42 trips the latter which, when released from the bottom of the coin, automatically swings with its nose uppermost in the path of the forward edge of the coin. As soon as the plunger 110 120 125 130

- 38 is released the spring 39 of the plunger projects the latter into its normal forward position releasing the tension on the coin, while the spring 30 through the arm 25 moves the rod 32 forwardly, and carries the coin therewith and against the nose of the pawl 42. The lower edge of the coin engaging the pawl 42 and the plunger 38 being carried forward by its spring 39, and the spring 30 urging the rod 32 forwardly, causes the coin to be released from between the plunger and plunger rod and to be deflected downwardly from the rod into the bottom of the cabinet.
- 15 A suitable tray or other receptacle 45 is mounted in the cabinet beneath the frame 24 for receiving coins released by the dog 42.
- 20 A relatively simple and expedient means is provided for detecting and throwing out coins of a spurious nature, wherein the checks or slugs are made of soft iron or the like which are susceptible to the influence of magnetism.
- 25 As is shown in the drawings, the coin slots 36 are grouped into pairs and the slots of a pair are provided with vertical openings 46 in their opposite sides so that the openings 46 face each other and the openings 30 are located near the upper ends of the coin slots 36 but are of sufficient width to admit of the free discharge or passage of slugs or the like which are deposited in the upper ends of the coin slots 36. Between each pair 35 of coin slots 36 is located a magnet 47 which may be of bar form as shown with the pole pieces or extremities disposed only at the top of each opening 46. When a spurious coin is deposited in the slot, the coin 40 is attracted by the magnet to the open side of the coin slot with the result that the coin is deflected downwardly toward and through the opening 46 of the coin slot.
- The magnet 47 is of sufficient strength 45 only to deflect the passage of the slug downwardly and laterally outward through the opening 46 so that after the slug has been deflected through the opening 46, the weight of the slug is such that it will not hang by 50 the magnet but will be finally released from the magnet near the central portion thereof so that the slug will fall downwardly between the slots 36 and therefore cannot pass to the coin holder 34.
- 55 It is obvious that various changes and modifications may be made in the details of construction and design of the above specifically described embodiment of this invention without departing from the spirit 60 thereof, such changes and modifications being restricted only by the scope of the following claims.
- What is claimed is:—
1. In a vending machine, a cabinet, a frame mounted substantially horizontally in
- the cabinet, a hollow plunger mounted in the forward end of the frame and biased to a forward position, a plunger rod mounted in the rear end of the frame in line with the plunger to receive the latter telescopically thereover when the plunger is depressed, a cross bar secured in the frame adjacent the normally disposed rear end of the plunger and having a plunger receiving opening therethrough, and a coin slot member secured through the wall of the cabinet and having a coin socket on its lower end fitting in said frame adjacent said cross member and in line with the forward end of the rod and having therein a coin receiving depression adapted to align with the plunger receiving opening of the cross member, said coin socket having means for interlocking engagement with said cross member to hold the coin socket and the slot member in adjusted position within the frame.
2. In a vending machine, a cabinet, a horizontal frame in the cabinet, a hollow plunger mounted in the forward end of the frame and biased to a forward position, a plunger rod mounted in the rear end of the frame in line with the plunger to receive the latter telescopically thereover when the plunger is depressed, a cross bar secured in the frame adjacent the normally disposed rear end of the plunger and having a plunger receiving opening therethrough, a coin slot member mounted in the cabinet and projecting through a wall thereof to receive a coin, a socket carried upon the lower end of the slot member and having a coin receiving depression therein in line with the forward end of the rod for supporting a coin from the slot member, and a pair of hooks carried by the socket member in engagement over said cross plate of the frame for interlocking the socket with the plate and holding the lower end of the socket member in line with the plunger.
- In testimony whereof I affix my signature. 110
